UNITED STATES PATENT OFFICE.

GEORGE W. DUVALL, OF DAVENPORT, IOWA, ASSIGNOR TO UNITED STATES BROOM COMPANY, OF DAVENPORT, IOWA, A CORPORATION OF IOWA.

COMBINED BROOM PRESSING AND NAILING MACHINE.

Application filed June 27, 1921. Serial No. 480,715.

To all whom it may concern:

Be it known that I, GEORGE W. DUVALL, a resident of Davenport, in the county of Scott and State of Iowa, and a citizen of the United States, have invented certain new and useful Improvements in Combined Broom Pressing and Nailing Machines, of which the following is a specification.

My invention is a combined broom pressing and nailing machine.

This invention embodies the idea of combining in one machine the pressing and nailing together, of metal case brooms and the like.

15 Heretofore this work has been performed in separate operations and largely by hand.

With the method now generally employed for making metal case brooms the nails are driven through the band one at a time by hand. The broom is then placed in a machine and pressed. It is quite plain that nails thus driven by hand are likely to tip over in pressing and further it is impossible to hold the broom tightly together when 25 made in this manner.

One of the dominant features of my present invention resides in driving the nails into the broom while it is under its maximum compression, the nails being clinched at that 30 moment prevent any relaxation after the broom is nailed which differs from the hand nailing method where one nail at a time is driven and it requires many blows of the hammer on a single nail; in other words my present invention includes the driving of a 35 plurality of nails at a single stroke while the broom is under pressure.

In the accompanying drawings; Fig. 1 is 40 a view in perspective of the essential elements of the device required to perform the work as outlined above.

Fig. 2 shows the main elements of a metal case broom assembled ready to press and nail together in the machine.

45 Fig. 3 shows the finished broom.

A quantity of broom corn shown by number 1 is inserted within the band 2. This thin metal band #2 is approximately circular in form. It is the butt or stalk end 50 of the corn which is inserted within the band. The handle 3 is then placed in the center of the broom corn at the stalk end of same, and the broom is ready for pressing and nailing. It should be understood that the assembling 55 of the broom elements above described is

done within the machine as shown in the dotted lines in Fig. 1.

After the broom has been assembled within the press as shown the operator then presses the foot treadle 4 which throws the machine 60 into operation thus pressing the broom into the form shown in Fig. 3, and nailing the same together while under pressure.

The numeral 5 is the main frame within which is the vertically sliding head 6. A 65 roller 7 is rotatably mounted on a shaft, which shaft is secured in the projection of the head 6 at its lower side.

The roller 7 rests on the cam 8. This cam is secured to a shaft rotatably held within 70 bearing A and B of frame 5. Secured to one end of this cam shaft is the master gear 9. The gear 9 meshes with the gear 10. Gear 10 is rotatably mounted on the shaft 11. It will be seen that gear 11 is provided with 75 one part of a dental coupling. The other half of the dental coupling 12 is mounted on the shaft 11 and while it rotates in unison with the shaft, is free to move longitudinally on the same. A disk 13 is attached to shaft 80 11. Mounted around shaft 11 and between disk 13 and coupling 12 there is the compression coil spring 14. This spring serves to push the two dental coupling members together except when they are forcibly held 85 apart.

The rods 15 and 16 are pivoted to bar 17 at their lower ends. This bar 17 is secured to frame 5. Pins are secured to each of the upper ends of the rods 15 and 16. The pins 90 extend into the groove in dental coupling member 12. Mounted between the rods 15 and 16 is a roller 28 free to rotate on its shaft 18. The gear 9 is provided with a projection 19 which holds the roller away from the gear, and by means of rods 15 and 16 holds the members of the dental coupling apart. The lower end of shaft 18 is provided with an arm 20. This arm is connected to the crank 21 by the rod 22. Crank 21 is attached 100 to the shaft 23. This shaft extends to the opposite side of the machine and has attached to it the treadle 4.

Belt pulley 24 and pinion 25 are mounted on and revolve in unison with shaft 26. 105 Pinion 25 meshes with gear 27. Gear 27 is attached to shaft 11. Assuming motion to be imparted to belt wheel 24, then all gears run continuously except gears 9 and 10. To cause these to revolve the operator presses 110

down on treadle 4. This action through the mechanical means shown draws the roller 28 off the narrow projection 19 thus allowing the spring 14 to force the dental coupling members together. The operator having removed his foot from the treadle 4 the spring 29 pushes the shaft 18 and the roller 28 to its original position. The dental coupling having been locked together the gear 10 nine will make one revolution and at the last of the revolution the projection 19 will force the coupling apart thus bringing 10 and 9 to a state of rest until the operation is repeated. During the revolution mentioned 15 the cam 8 revolves forcing the roller 7 and the heads 6 upward thus compressing the broom. The form of cam 8 is such as to hold the compressed broom under pressure long enough for the nailing device to perform its 20 work while driving the nails through the band 2 as shown in Fig. 3.

Mounted on the frame 5 are the brackets 30 and 31. These brackets serve as guides to retain in a vertically slidable position the 25 punchhead 32. This head is operatively connected by the eccentric rod 33 and 34 with the eccentrics 35 and 36. Attached to the head 32 are any desired number of punches 37. These punches move vertically 30 and in unison with the head 32. Their function is to descend on the tops or heads and drive or press them through the band into the broom corn. The nails are conveyed from the nail hopper 38 and delivered under 35 the punches by the tubes 39. What is known as the pick-off of any well-known design is employed adjacent to the hopper to insure only one nail at a time being delivered below the plungers.

40 The eccentrics 35 and 36 are secured on shaft 40. This shaft revolves in bearings C and D. The chain-wheel 41 is rotatably mounted on shaft 40. Wheel 41 by means of the chain-belt 42 revolves continuously 45 and in unison with shaft 26. The eccentrics 35 and 36 are caused to make one revolution and then rest by any of the well-known knock-out devices, now on the market. Such a device is shown by the numbers 43, 44, and 50 45. In order to trip the knock-out and the nailing attachment in motion while the broom is under compression the trip rod 46 is attached to head 6. As head 6 nears the limit of its upward travel the rod 46 comes 55 in contact with the knockout device and sets the same in motion.

With this invention the broom is tightly 60 pressed and the nails are driven while the broom is under pressure which insures that they go straight through the broom. By using nails of the right length the points will come in contact with the lower portion of the band and turn and clinch tightly on the broom corn or other fibre. The broom 65 is then turned over and the operation of

pressing and driving another set of nails is repeated.

I claim—

1. In a broom pressing and nailing machine, the combination with a frame, of a continuously rotating shaft, gearing driven continually thereby, a compression or sliding head, a cam for actuating said head, means for imparting a single rotation to said cam from said continuously rotating 70 gearing for compressing a broom, said means including a shaft upon which the cam is mounted, a gear on said shaft, a dental coupling intermittently meshed for driving said gear from said continuously driven 75 gearing, a yoke, controlling the meshing and engaging one half of said coupling, a roller carried by the yoke and normally pressing against said gear and arranged to permit meshing of the coupling and rotation of the 80 gear and cam, a stop on the gear for engaging the roller and moving it laterally and actuating the yoke to unmesh the coupling, means actuating by the operator for moving the roller from its engagement with 85 the stop and permitting the meshing of the coupling and the rotation of the cam for one revolution, and means for nailing the broom while under compression.

2. In a broom pressing and nailing machine, the combination with a frame, of a continuously rotating shaft, gearing driven continually thereby, a compression or sliding head, a cam for actuating said head, means for imparting a single rotation to said cam from said continuously rotating gearing for compressing a broom, said means including a shaft upon which the cam is mounted, a gear on said shaft, and a dental coupling intermittently meshed for driving said gear from said continuously driven 90 gearing, a yoke controlling the meshing and engaging one half of said coupling, a roller carried by the yoke and normally pressing against said 95 gear and arranged to permit meshing of the coupling and rotation of the gear and cam, a stop on the gear for engaging the roller and moving it laterally and actuating the yoke to unmesh the coupling, and means actuated by the operator for moving the roller from its engagement with the stop and permitting the meshing of the coupling and the rotation of the cam for one revolution.

3. In a broom pressing and nailing machine, the combination with a frame, of a continuously rotating shaft, gearing driven continually thereby, a compression or sliding head, a cam for actuating said head, means for imparting a single rotation to said cam from said continuously rotating 110 gearing for compressing a broom, and intermittent means driven by said continuously 115 rotating gearing for driving nails in a broom while under compression from said sliding head, said last-mentioned means automati- 120 125 130

cally actuated by the compressing movement of said sliding head.

4. In a broom pressing and nailing machine, the combination with a frame, of a continuously rotating shaft, gearing driven continually thereby, a compression or sliding head, a cam for actuating said head, means for imparting a single rotation to said cam from said continuously rotating gearing for compressing a broom, and intermittent means driven by said continuously rotating gearing for driving nails in a broom while under compression from said sliding head, said means including a shaft, eccentric on the shaft, and plungers actuated by said eccentric, and means automatically operated upon the compressing movement of the head for actuating said last-mentioned shaft and eccentric.
5. In a broom pressing and nailing machine, the combination with a frame, of a continuously rotating shaft, gearing driven continually thereby, a compression or sliding head, a cam for actuating said head, means for imparting a single rotation to said cam from said continuously rotating gearing for compressing a broom, intermittent means driven by said continuously rotating gearing for driving nails in a broom while under compression from said sliding head, said means including a shaft, eccentric on the shaft, and plungers actuated by said eccentric, and means for intermittently imparting rotary movement to said eccentric, controlled automatically by the compressing movement of said head, said means including a finger on the sliding head, a bell crank lever on the frame, and a knock-out clutch on the shaft carrying the eccentric.
6. In a broom pressing and nailing machine, the combination with a frame, of a continuously rotating shaft, gearing driven continually thereby, a compression or sliding head, a cam for actuating said head, means for imparting a single rotation to said cam from said continuously rotating gearing for compressing a broom, intermittent means driven by said continuously rotating gearing for driving nails in a broom while under compression from said sliding head, said means including a shaft, eccentric on the shaft, and plungers actuated by said eccentric, and means for intermittently imparting rotary movement to said eccentric, controlled automatically by the compressing movement of said head, said means including a finger on the sliding head, a bell crank lever on the frame, and a knock-out clutch on the shaft carrying the eccentric.

trics on the shaft, and plungers actuated by said eccentric, and means imparting rotary movement to said eccentric, said nail driving mechanism automatically controlled by the movement of said sliding head so that the nailing is done while the broom is under compression.

6. In a broom pressing and nailing machine, the combination with a frame, of a continuously rotating shaft, gearing driven continually thereby, a compression or sliding head, a cam for actuating said head, means for imparting a single rotation to said cam from said continuously rotating gearing for compressing a broom, intermittent means driven by said continuously rotating gearing for driving nails in a broom while under compression from said sliding head, said means including a shaft, eccentric on the shaft, and plungers actuated by said eccentric, and means for intermittently imparting rotary movement to said eccentric, controlled automatically by the compressing movement of said head, said means including a finger on the sliding head, a bell crank lever on the frame, and a knock-out clutch on the shaft carrying the eccentric.

In testimony whereof I hereunto affix my signature.

GEORGE W. DUVALL.
